(57) **CLAIM**

The ornamental design for a telescopic sight mount, as shown and described.

DESCRIPTION

FIG. 1 is an isometric view of a telescopic sight mount showing my new design;

FIG. 2 is another isometric view of the telescopic sight mount of FIG. 1;

FIG. 3 is a rear elevational view of the telescopic sight mount of FIG. 1;

FIG. 4 is a front elevational view of the telescopic sight mount of FIG. 1;

FIG. 5 is a right side elevational view of the telescopic sight mount of FIG. 1;

FIG. 6 is a left side elevational view of the telescopic sight mount of FIG. 1;

FIG. 7 is a top plan view of the telescopic sight mount of FIG. 1; and,

FIG. 8 is a bottom plan view of the telescopic sight mount of FIG. 1.

The broken lines shown in the Figures are included for the purpose of illustrating portions of the telescopic sight mount that form no part of the claimed design.
